(57) **CLAIM**

The ornamental design for a display screen with graphical user interface, as shown and described.

DESCRIPTION

FIG. 1 is a front view of a display screen with graphical user interface showing a first image of the claimed design in a first embodiment.

FIG. 2 is a second image of the first embodiment.

FIG. 3 is a front view of a display screen with a graphical user interface showing a first image of the claimed design in a second embodiment.

FIG. 4 is a second image of the second embodiment.

FIG. 5 is a front view of a display screen with a graphical user interface showing a first image of the claimed design in a third embodiment.

FIG. 6 is a second image of the third embodiment.

FIG. 7 is a front view of a display screen with a graphical user interface showing a first image of the claimed design in a fourth embodiment.

FIG. 8 is a second image of the fourth embodiment.

FIG. 9 is a front view of a display screen with a graphical user interface showing a first image of the claimed design in a fifth embodiment.

FIG. 10 is a second image of the fifth embodiment.

FIG. 11 is a front view of a display screen with a graphical user interface showing a first image of the claimed design in a sixth embodiment.

FIG. 12 is a second image of the sixth embodiment.

FIG. 13 is a front view of a display screen with a graphical user interface showing a first image of the claimed design in a seventh embodiment.

FIG. 14 is a second image of the seventh embodiment.

FIG. 15 is a front view of a display screen with a graphical user interface showing a first image of the claimed design in an eighth embodiment.

FIG. 16 is a second image of the eighth embodiment.

FIG. 17 is a front view of a display screen with graphical user interface showing a first image of the claimed design in a ninth embodiment.

FIG. 18 is a second image of the ninth embodiment.

FIG. 19 is a front view of a display screen with a graphical user interface showing a first image of the claimed design in a tenth embodiment.

FIG. 20 is a second image of the tenth embodiment.

FIG. 21 is a front view of a display screen with a graphical user interface showing a first image of the claimed design in an eleventh embodiment;

FIG. 22 is a second image of the eleventh embodiment.

FIG. 23 is a front view of a display screen with a graphical user interface showing a first image of the claimed design in a twelfth embodiment.

(Continued)

FIG. 24 is a second image of the twelfth embodiment. FIG. 25 is a front view of a display screen with a graphical user interface showing a first image of the claimed design in a thirteenth embodiment.

FIG. 26 is a second image of the thirteenth embodiment. FIG. 27 is a front view of a display screen with a graphical user interface showing a first image of the claimed design in a fourteenth embodiment; and,

FIG. 28 is a second image of the fourteenth embodiment. The first image in every embodiment shows the graphical user interface in an initial state.

The second image in every embodiment shows the graphical user interface in a state after the initial state. The transition between the first image and the second image of each embodiment forms no part of the claimed design.

The outer broken lines in the figures show a display screen or portion thereof, and the other broken lines in the figures show portions of the graphical user interface. The broken lines form no part of the claimed design.
